SHADE ROLLER OPERATING MEANS

Samuel W. Paige, Spout Spring, Va.

Application January 19, 1937, Serial No. 121,334

2 Claims. (Cl. 156—28)

This invention relates to what is believed to be a structurally new and novel shade roller support and operating means therefor, wherein the arrangement is such as to substitute a manually controlled operating mechanism for the so-called conventional pawl and ratchet spring actuating means.

Seeking to improve on known prior patented and marketed arrangements, I have perfected aptly fitted structural details mutually cooperating in a well planned assemblage constituting what is believed to be a desirable and appreciable contribution to the art.

In reducing to actual practice the principles of my ideas, I have found it expedient and practicable to utilize a pair of similar supporting brackets provided with ball bearing devices to rotatably and effectively support the trunnion equipped ends of the shade roller, whereby to facilitate raising and lowering the shade.

The principal feature of the invention is, however, predicated on the adoption and use of escapement-like pawl and ratchet means wherein the ratchet wheel is directly coordinated with a pull chain having its free workable ends depending in parallelism within convenient reach to facilitate positioning the shade in the desired position and satisfactorily holding it set in such position.

Other features and advantages will become more readily apparent from the following description and drawings.

In the drawings:

Figure 1 is an elevational view, essentially in section, showing the complete assemblage as constructed in accordance with my personal ideas.

Figure 2 is an end view of Figure 1 observing it in a direction from left to right.

Figure 3 is a sectional view which may be said to be taken approximately on the plane of the line 3—3 of Figure 1.

Figure 4 is a detail elevational view of the left hand bracket and its appurtenances, the chain being removed for clearness of illustration.

Figure 5 is a perspective view of the spring pawl and its attaching element.

Figure 6 is what may be designated as an outside elevational view of the right hand bracket shown in Figure 1.

Figure 7 is a fragmentary perspective view of one end portion of the shade drum or roller.

In the drawings the wooden shade roller is denoted by the numeral 6 and this embodies a central axle or shaft 9 whose ends extend beyond the corresponding ends of the roller proper and

constitute trunnions or journals 10 and 11. The shade, which may be of any appropriate construction, is denoted by the numeral 12 and is shown wound on the roller as seen in Figure 1.

The so-called right hand supporting and hanger fixture is differentiated by the numeral 13. It comprises an apertured attaching flange 14 and an outstanding right angularly disposed plate 15. The central portion of the plate indicated at 16 in Figure 6 is formed into a cup 17 to accommodate a notched roller bearing unit 18. The entrance notch 19 permits insertion and removal of the trunnion 11.

The left hand or opposite supporting fixture is denoted by the numeral 20. This also includes 15 an apertured attaching flange 21 and an outstanding wing or plate 22. As seen to advantage in Figure 4, the central longitudinal edge portion of the plate is formed into a circular cup 23, facing outwardly and containing therein a suitable ball race or bearing unit denoted by the numeral 24. This arrangement provides the desired anti-friction support or bearing for the trunnion 10. Consequently, by supporting both ends of the roller in ball bearing races, the shade may be wound and unwound easily.

Attention is now called to the numeral 25 in Figure 4. This comprises a suitable receptacle, guiding and tracking adapter for the pull chain 26. It includes a suitably curved track or hanger 30 flange 27 having down-turned guides 28 at opposite ends. These guides lead the chain-ends down into desired parallelism for convenient reach and operation. The numeral 29 designates an attaching flange, and this is secured to the inner side 35 of the bearing cup 23. This adapter bracket 25 serves to accommodate the marginal tubed portion of the escapement or ratchet wheel 30, this being keyed on the trunnion 10 and interposed between the bearing cup 23 and said adapter fixtures 25, as well as the adjacent end of the wooden part of the roller 8.

Also attached to the bearing cup is an L-shaped member 31 carrying the spring trip or pawl 32. The pawl is located for releasable ratcheting engagement with the teeth of the ratchet wheel 30.

Assuming that the device is set up and assembled as shown in the drawings, and referring to Figure 2, it is evident that by pulling either end of the chain 26, the links thereof being in 50 mesh or tracking connection with the teeth of the gear wheel, said wheel is rotated and this in turn rotates the shade roller, permitting winding or unwinding of the shade depending on the direction of movement of the chain. The spring 55

pawl provides the desired ratcheting action and also serves to retain the ratchet wheel set when the shade is located, through the instrumentality of the chain, in the desired position.

5 It follows, therefore, that the gist of the invention is predicated upon a pair of companion supporting brackets attachable to the frame and provided with roller bearing devices to accommodate journals or trunnions on the opposite ends 10 of the shade roller. This is one feature. Secondly, novelty is predicated upon the chain actuated ratchet wheel and pawl and ratchet features cooperable with the chain. More specifically, novelty is predicated on the individual fixtures 15 13, 20, and the accessories 25 and 31 and 32 seen in Figure 4. Or stated otherwise, novelty is based on the structural coordination of features in combination as well as the individual component parts which mutually cooperate to render the structure efficient and reliable.

20 It is thought that the description taken in connection with the drawings will enable a clear understanding of the invention to be had. Therefore, a more lengthy description is thought unnecessary.

25 While the preferred embodiment of the invention has been shown and described, it is to be understood that minor changes coming within the field of invention claimed may be resorted to if desired.

30 I claim:
1. In a structure of the class described, a pair

of companion supporting and attaching brackets, a shade roller having trunnions at its opposite ends, said brackets being provided with bearings receiving the trunnions to facilitate rotation of the roller in either direction, a toothed wheel connected with one trunnion, a chain hanger connected with one bracket and having a curved flange extending under the lower part of the wheel, semi-tubular guides extending downwardly and outwardly at the ends of said flange and a 10 chain having an intermediate portion passing over the flange and through the guides and said portion of the chain engaging the teeth at that part of the wheel located in the hanger.

2. In a structure of the class described, a pair 15 of supporting brackets, a roller having trunnions at its ends rotatably arranged in said brackets, a toothed wheel on one trunnion, a chain hanger connected with one bracket and having a downwardly curved flange for receiving the lower part 20 of the wheel and downwardly and outwardly curved guides at the ends of the flange, a chain having an intermediate portion passing over the flange and through the guides with its links engaging the lower teeth of the wheel, a small bracket supported from that bracket carrying the hanger and a spring detent carried by the small bracket and engaging the upper portion of the toothed wheel to frictionally hold the same 25 against movement.

SAMUEL W. PAIGE.
